UNITED STATES PATENT OFFICE

HARRY R. PRIEST, OF LOUDONVILLE, OHIO

DENTAL POLISHER

Application filed September 12, 1930. Serial No. 481,552.

This invention relates to dental polishers of the power driven type used by dentists and has for an object to provide a polisher which will have a stem or shank reinforced to withstand breaking when considerable pressure is applied and which will employ a single unitary solid tuft of stiff boar bristles or badger hair or the like which will remain rigid under the great pressure used to polish and clean teeth.

Usually the cleaners and polishers used by dentists for mechanically cleaning and polishing the teeth by power driven apparatus have bristles which bend or have a hinge effect when pressure is applied and thus become quickly ineffective for cleaning and polishing teeth and also spread apart and become irregular so that jagged outstanding bristles are presented to injure the gums and soft membranes and tissues of the mouth. Also polishing compounds containing more or less grit or stone or similar abrasive material must be used to compensate for the hinge action of the bristles. To overcome both of these difficulties the present invention employs a rigid stiff compact unitary bristle element which will retain its contour as well as the length and thickness thereof intact under pressure up to twenty pounds, and more, which great pressure is necessary to bring forth the natural luster and polish of the teeth. At the same time such pressure, entirely too great to be withstood by ordinary mechanical cleaners and polishers now in use, obviates the necessity of the use of abrasives which grind away the enamel which is none too thick at best. By virtue of the shape retaining action of the bristle component, that is, absence of any hinge effect whatever, there will be no bristles to stand out laterally and injure the tissues when the dental engine is operating to rotate the tool at high speed during the cleaning and polishing operation.

With the above and other objects in view the invention consists in certain novel details of construction and combination of parts hereinafter fully described and claimed, it being understood that various modifications may be resorted to within the scope of the

appended claim without departing from the spirit or sacrificing any of the advantages of the invention.

In the accompanying drawing forming part of this specification,

Figure 1 is a side elevation of a dental polisher constructed in accordance with my invention,

Fig. 2 is an enlarged sectional view through the dental polisher,

Fig. 3 is a side elevation, partly broken away, showing a modified form of the invention, and

Fig. 4 is a side elevation, partly broken away, showing still another modification of the invention.

Referring now to the drawing in which like characters of reference designate similar parts in the various views, the dental polisher is shown to comprise a shank 10 which terminates in a head or socket 11, both the shank and socket preferably being formed of hard rubber so as not to injure the gums, and preferably the socket is reinforced axially by a stiff metal rod 12. The shank is receivable in the chuck or hand piece of the dental engine in the usual manner and by virtue of the central stiffening core or rod 12, it is resistant to buckling or breaking when the great pressures attended upon the use of the device are imparted.

The bristle component comprises a single unitary compact stiff tuft 13 of boar bristles, badger hair, fiber bristles or other suitable rigid stiff unyielding material so compactly assembled as to practically resist penetration of a pin or needle thrust into the structure. In ordinary practice, the bristles are securely bound together and firmly embedded in a hard rubber base 14, that is, the bristles are rubber set to positively prevent any change in cross dimension of the bristle component. Ordinarily, the bristle component projects about $\frac{3}{8}$ to $\frac{1}{8}$ of an inch above the base and is about one-fourth inch wide, or substantially the same in width as the length of the projecting portion of the bristle component or tuft. In practice, the unitary stiff assembly of rigid bristles resists distortion from either longitudinal dimension or trans-

verse dimension under pressure up to and beyond twenty pounds and exhibits no hinge effect or bending effect whatsoever as is customary with the usual bristle equipped polishing tools used by dentists with power apparatus.

It will be specifically pointed out that ordinarily the bristle component is fastened to the shank component by rivets or staples or similar devices which are prone to break even under the light pressures applied in the usual practice and present the hazard of injury to the gums or soft tissues of the mouth. To positively obviate accidental displacement of the bristle component from the shank component, in the present invention, I preferably drive the base 14 into the socket 11 with considerable pressure, that is, the parts having a driving fit so that relative movement of the same is positively prevented. Furthermore, to make sure that accidental displacement of the parts will not occur while in use, a pin 15 is passed through the socket member 11 and through the base member 14 to couple these parts rigidly in a single unitary non-distortable structure.

The bristle component constructed as above described needs no abrasive material to restore the high and natural polish and luster of the teeth, since the abnormally great pressure which the tool will withstand when in use serves to effectively remove mucin film, stains, tartar and the like without the use of injurious abrasives which in time will destroy the enamel of the teeth.

In Figures 3 and 4 there are shown modified forms of the invention, the same varying somewhat in shape and size as to the bristle component to adapt the device for various conditions of service. In Fig. 3 the bristle component 16 is of considerable width or cross diameter and is embedded or rubber set in a hard rubber base 17 which is forced into a socket member 18 and coupled thereto by a pin 19. The socket member is provided with an axial shank 20 which is axially reinforced to withstand buckling or breakage by means of a metal bar 21.

In Figure 4 the bristle component 22 is illustrated as bullet shaped or substantially conical. The bristle component is also in this modification rubber set or embedded in a hard rubber base 23 which is driven into a socket 24 and rigidly connected thereto by a pin 25. The socket is rounded exteriorly at the base thereof to conform in streamline to the bristle component. The socket terminates in an axial shank 26 which is centrally reinforced longitudinally by a metal rod 27.

In both the preferred form and the modified form of the invention, the socket member and shank is formed of a single integral piece of material, preferably hard rubber, so that injury to the gums will be prevented

should the tool slip during the cleaning and polishing operation.

Having thus described the invention, I claim:

A dentist's tooth cleaning and polishing tool comprising a shank adapted to be received in the chuck of a dental engine and terminating in a socket, a single short wide unitary cylindrical tuft of stiff bristles, a hardened plastic base for said tuft disposed in said socket and permanently clamping said bristles in intimate contact with each other throughout their entire length, said tuft projecting about $\frac{3}{2}$ " to $\frac{1}{4}$ " beyond the socket and being about the same in width as the length of the projecting portion whereby spreading apart of the bristles at their exposed ends under great pressure is prevented.

In testimony whereof I affix my signature.
